GRID CORE FOR A TRANSLUCENT BUILDING PANEL OR SIMILAR ARTICLE

Robert R. Keller, 41 Union St., Manchester, N.H.

Filed Apr. 8, 1964, Ser. No. 79,409

Term of patent 14 years

(Cl. D13—1)

Fig. 1.

Fig. 2.

Fig. 3.

FIG. 1 is a perspective view of a grid core for a translucent building panel, showing my new design;

FIG. 2 is a vertical edge view thereof; and

FIG. 3 is an end view thereof.

The side opposite that shown in FIGURE 1 is substantially respectively identical therewith.

I claim:

The ornamental design for a grid core for a translucent building panel or similar article, substantially as shown and described.
